END MILL

Carl G. Gase, Parma, Ohio, assignor to Weldon
Tool Company, Cleveland, Ohio, a corporation
of Ohio

Application March 14, 1936, Serial No. 68,897

4 Claims. (Cl. 29—103)

My invention relates to end mills and other cutting tools.

An object of my invention is to provide an end mill having greater strength and supporting action for its cutting edges.

Another object is to provide an end mill having relatively short cutting edges and a relatively large face between the cutting edges.

Another object is to provide an end mill having cutting edges substantially confined to the end of the fillet.

Another object is to provide an end mill having a central depressed portion in the body of the end mill at the cutting end so as to provide clearance between the said body and the mass to be cut.

Another object is to provide a depressed portion in the cutting end of an end mill, which depressed portion has sloping sides extending in a gradual and positive slope from the axial center of the end mill to the cutting edges.

A still further object is to provide an end mill having an arcuate depressed portion at its cutting end, the sloping sides of which arcuate depressed portion act as a brace for the cutting edges of the end mill.

A still further object is to provide an arcuate depressed portion in the cutting end of an end mill, the sloping sides of which arcuate portion act as a brace for the peripheral portion of the end mill at the cutting end.

Other objects and a fuller understanding may be had by referring to the accompanying drawing, taken in conjunction with the following description and claims, in which:

Figure 1 represents a side view of my end mill;

Figure 2 represents a view of my end mill with portions of the cutting end cut away to give a fragmentary view of the cutting end;

Figure 3 represents a left-hand end view looking at the cutting end of the end mill in Figure 1;

Referring to Figure 1, I show an end mill 15 having a flat surface 16 on its engaging end for securing engagement of the end mill 15 to a shop

machine. The end mill 15 has a plurality of spiral flutes 17 formed therein, leaving the fillets 18 in raised position extending longitudinally of the end mill 15 between the flutes 17. As shown in the illustration, the fillets 18 are integral with

the end mill and are extended in a spiral manner along the end mill. The body portion or core 19 is shown in dotted lines and represents the body of the end mill 15 within the fillets 18. Each fillet 18 has a narrow side 25 and a wider side

26 which converge to form a longitudinal edge

28 extending along each of said fillets. Upon the cutting end of each fillet is a cutting edge 20 extending toward the axial center of the end mill.

Extending centrally of the cutting end of the end mill 15, between the cutting edges 20, is an arcuate depressed portion 22. The cutting edges 20 are substantially confined to ends of the fillets 18 and the arcuate depressed portion 22 extends across the end of the body portion 19. The cutting clearances 21 extend in a slightly sloping manner from the cutting edges 20. There is a recess 24 cut into the end of the body portion 19 at the terminus of each of the fillets 18. These recesses 24 extend inwardly and are somewhat sloping. The flute clearance 23 extends from each cutting clearance 21 back to each recess 24 and slopes from the cutting clearance down to the niche or recess 24 and also slopes slightly outwardly so as to converge into the flute.

In Figure 2, the arrangement of the parts upon the cutting end is well shown by cutting away a portion of the cutting end. The dead center hole 27 in the axial center of the end mill is the conventional hole used in making the tool. The arcuate depressed portion is shown extending substantially across the end of the end mill 15 and between the cutting edges 20. The fillet upon the rear side of the end mill is shown as extending out beyond the arcuate depressed portion, and the narrower side 25 of the fillet 18 is shown as pointing down. The longitudinal edges 28 are shown as terminating at the cutting edge.

Figure 3 being a view looking at the left end 35 of the end mill of Figure 1, shows in detail the arrangement of the respective parts upon the cutting end of the end mill. The arcuate depressed portion 22 is shown as extending across substantially the end of the body of the end mill, having 40 the dead center hole 27 in the axial center thereof. As the cutting edges 20 are slightly undercut, only the wider side 26 of each fillet is shown spirally up the end mill. The cutting clearance 21 upon each end of the fillet is shown as defining a cutting edge 20 upon one side of the cutting clearance 21. Cut down into the end mill is the recess or inward cut 24 at the end of each flute 17, so that the depression of each flute 17 is carried inwardly of the end mill toward the 50 axial center thereof. The recess 24 acts as a limit which aids in defining the extent of the flute clearance 23 so that in grinding the flute clearance 23, the grinder need not be brought too close to the cutting edges 20. The flute clearance 23 55

is shown as extending between each of the recesses 24 and the cutting clearances 21. The surface of the flute clearances is sloped at a slight incline from the cutting clearances 21 down to 5 the recess 24 and also slopes slightly back to converge with the wider side 26 of each fillet 18.

It is seen by referring to Figures 1, 2, and 3, that the arcuate depressed portion 22 by its arcuate nature has walls which act as a substantial 10 brace and support for the cutting edges 20 on the end of each fillet. It is also seen that such a structure permit the confining of the cutting edges 20 to the cutting end of the fillet without substantially extending inwardly upon the body 15 of the end mill. The absence of this supporting structure would necessitate having much wider cutting edges and extending inwardly in order to give sufficient strength to the cutting edges. It is seen that the stress against the cutting edges 20 20 is met not only by the bracing action of the fillet back of each cutting edge, but also by the bracing action of the wall of the arcuate depressed portion 22.

Since the end mill is moved laterally as well as 25 rotatively, it is necessary to have a clearance between the center or body of the end mill and the mass to be cut. This limits the width of the cutting edges. The advantage of my end mill with the cutting edges upon the end of the fillets 30 and a relatively wide depressed arcuate portion between them, having the sloping walls supporting and bracing these short cutting edges, is such that the short cutting edges are not prone to break off and chip because of lack of support. 35 My structure in its bracing action gives maximum strength to the short cutting edges and permits them to be substantially confined to the cutting end of the fillet.

Although I have described my invention with 40 a certain degree of particularity, it is understood that the present disclosure has been made only by way of example and that numerous changes in the details of construction and the combination and arrangement of parts may be resorted to 45 without departing from the spirit and the scope of the invention as hereinafter claimed.

I claim as my invention:

1. An end mill having a plurality of cutting edges on a lateral end face of said mill comprising, in combination, a fluted member having a body portion and a plurality of fillets extending along the body portion, said fillets having longitudinal cutting edges extending thereon, a lateral cutting edge on the lateral end face of each 50 of said fillets, each said lateral cutting edge being disposed substantially at right angles to the longitudinal axis of said mill and the outer end of each said lateral cutting edge meeting the longitudinal cutting edge of each said fillet to form a substantially sharp cutting corner, the length of each of said lateral cutting edges being substantially limited to the depth of the flutes, said body portion having a depressed portion intermediate of the inner ends of the lateral cutting edges, said depressed portion being shallow 55 adjacent the inner ends of the lateral cutting edges and having a gradual slope and being deeper inwardly towards the longitudinal axis of the end mill.

2. An end mill having a plurality of cutting edges on a lateral end face of said mill comprising, in combination, a fluted member having a body portion and a plurality of fillets extending

along the body portion, said fillets having longitudinal cutting edges extending thereon, a lateral cutting edge on the lateral end face of each of said fillets, each said lateral cutting edge being disposed substantially at right angles to the longitudinal axis of said mill and the outer end of each of said lateral cutting edge meeting the longitudinal cutting edge of each said fillet to form a substantially sharp cutting corner, said fluted member having a gradually sloping depressed end portion extending across the end of said body portion intermediate of said lateral cutting edges and having boundary points located near the outer edge of the body portion, the inner ends of the lateral cutting edges being 15 adjacent the outer boundary of the depressed end portion and extending outwardly toward the longitudinal cutting edges.

3. An end mill capable of cutting at a marked increase in speed as compared with other end 20 mills in standard practice and at the same time maintaining cutting edges comparable with the cutting edges of said other end mills, said end mill comprising a fluted body member having a plurality of fillets with longitudinal cutting edges 25 extending therealong, a lateral cutting edge on the lateral end face of each of said fillets, each said lateral cutting edge being disposed substantially at right angles to the longitudinal axis of said mill and the outer end of each said lateral cutting edge meeting the longitudinal cutting edge of each said fillet to form a substantially sharp cutting corner, the cutting end of the said end mill being modified from standard practice by having a substantial decrease in the length 30 of the lateral cutting edges and by having a substantial increase in distance between the inner ends of the lateral cutting edges and by having a relatively wide and shallow depressed portion intermediate the inner ends of the lateral cutting 35 edges, said depressed portion extending to the inner ends of the lateral cutting edges and deepening inwardly toward the longitudinal axis of the end mill.

4. An end mill capable of cutting at a marked 40 increase in speed as compared with other end mills in standard practice and at the same time maintaining cutting edges comparable with the cutting edges of said other end mills, said end mill comprising a fluted body member having a 45 plurality of fillets with longitudinal cutting edges extending therealong, a lateral cutting edge on the lateral end face of each of said fillets, each said lateral cutting edge being disposed substantially at right angles to the longitudinal axis of 50 said mill and the outer end of each said lateral cutting edge meeting the longitudinal cutting edge of each said fillet to form a substantially sharp cutting corner, the cutting end of the said end mill being modified from standard practice 55 by having a substantial decrease in the length of the lateral cutting edges and by having a substantial increase in distance between the inner ends of the lateral cutting edges and by having a relatively wide and shallow depressed portion 60 intermediate the inner ends of the lateral cutting edges, said depressed portion being shallow adjacent the inner ends of the lateral cutting edges and having a gradual slope and being deeper 65 inwardly towards the longitudinal axis of the end 70 mill.

CARL G. GASE.
